MILL PLATE RESHARPENING MACHINE

Jose C. H. Leon, Tegucigalpa, Honduras

Application August 23, 1938, Serial No. 226,395

5 Claims. (Cl. 51—92)

My invention relates to the treatment of mill plates and includes among its objects and advantages the provision of an improved mill plate resharpening machine.

5 An object of my invention is to provide a device of the type described including a grinding wheel and a movable support for a mill plate to be resharpened and in which novel means are incorporated for turning the mill plate step by step together with novel means for advancing the mill plate towards the grinding stone to compensate wear on the latter.

10 A further object is to provide a device of the type described including a rotary grinding wheel arranged to be adjusted to different angles in which means are incorporated for bringing a mill plate into grinding relation with the stone and in which novel means are incorporated for turning the mill plate step by step as an incident 15 to movement of the mill plate relatively to the stone for grinding purposes.

15 Another object is to provide a machine of the type described including a rotary grinding stone including novel reciprocatory means for manipulating a mill plate in grinding relation with the stone and in which ratchet mechanism is employed for automatically turning the mill plate to the next grinding position upon completion 20 of each succeeding grinding action.

25 With these and other objects in view, this invention consists in certain novel features of construction, combination and arrangement of parts to be hereinafter more fully described and claimed.

30 For a complete understanding of my invention, reference is to be had to the following description and accompanying drawings, in which

Figure 1 is an elevational view of a machine embodying my invention;

35 Figure 2 is a fragmentary view of the structure illustrated in Figure 1;

Figure 3 is a view taken from the position indicated by line 3—3 of Figure 2;

Figure 4 is a sectional view along the line 4—4 40 of Figure 1;

Figure 5 is a sectional view along the line 5—5 of Figure 1;

Figure 6 is a detail view of the ratchet mechanism; and

45 Figure 7 is a diagrammatic face view of a mill plate which may be sharpened in the machine.

In the embodiment selected to illustrate my invention I make use of a base 10 including a flange 11 of relatively large diameter for supporting the machine in an upright position on a

5 floor or other support 12. If desirable the flange 11 may be bolted to the supporting structure. Flange 11 is cast intricately with the post 13 which is hollow and cast integrally with a hollow angular post 14. Within the post 13 I fixedly connect one end of a tube 15 through the medium of a set screw 16. Tube 15 constitutes a support for the mill plate holder and actuator 17. Post 14 supports a tubular support 18 which includes an offset end 19 fixedly secured to the post 18 10 by a coupling element 20. Post 18 carries the grinding unit 21.

15 Adjacent the upper end of the post 18 I mount a flange 22 which includes a collar 24 having threaded connection at 25 with the post 18. Upon the end of the post 18 I mount a base plate 26 having a collar 27 rotatably related to the end of the post. Base plate 26 carries a fixed screw 28 projecting in the direction of the flange 22 and provided with an adjustable nut 29 which 20 may be brought into pressure relation with the flange 22 for restraining the base plate 26 from relative rotary movement. Upon the peripheral margin of the flange 26 I provide graduation 30 while the base plate 26 carries a fixed needle or 25 pointer 31 which is related to the graduation 30 to indicate angular adjustment of the base plate 26 about the axis of the tube 18.

30 On the base plate 26 I mount a guide 32 and secure the guide in fixed position by bolt 33 passing through the plate 26 and threaded into the guide. Guide 32 is grooved, as at 34, for slidably receiving the tongue 35 formed on the gear box 36. The transmission of the gear box is connected with a drive shaft 37 having a grooved 35 pulley 38 for connection with a drive belt. The rotary grinding stone 39 is operatively connected with the transmission in the gear box. Since speed increasers of the gear type are well known in the art, the transmission need not be described 40 in further detail.

45 Projecting laterally of the base plate 26 is an arm 40 which may be cast intricately with the plate and the collar 27. Arm 40 is provided with a threaded opening 41 having threaded relation 45 with an advancing screw 42 having its end 43 arranged in abutting relation with the gear box 36, see Figure 2. Gear box 36 may be adjusted in the direction of the mill plate unit 17 through rotation of the screw 42 which may be consumed 50 through the medium of a handle 44 having pivotal connection at 45 with the screw. Screw 45 may be secured against rotation through the medium of a screw 46 threaded into the end 55 of the arm 40. Adjustment of the gear box

36 toward the mill plate unit 17 is consummated against the tension of a spring 47 having one end anchored at 48 to the flange 49 carried by the arm 40 and its opposite end anchored at 5 50 to the gear box. Rotation of the screw 42 in the opposite direction permits rearward movement of the gear box for moving the grinding stone 39 away from the mill plate unit because of the spring 47. For grinding purposes the gear 10 box unit is positively advanced through the medium of screw 42 and the screw constitutes an unyielding abutment for resisting the forces applied to the grinding stone 39.

Base plate 26 includes an upstanding flange 51 slotted at 52 for accommodation of a set screw 53 threaded into the gear box 36. The gear box includes a finger 54 which projects through the slot 52 and is readably related to graduation 55 on the outer face of the flange 51 along the slot 20 52 for indicating the advance position of the grinding stone 39. Flange 49 supports a vertical bar 56 which carries the grinding stone dresser unit 57. Unit 57 may be adjusted longitudinally of the arm 56 through the medium of a fastening 25 mount 58 extending through the slot 59 in the arm. Arm 56 carries a bolt 60 extending through a slot 61 in the flange 49. Bolt 60 is provided with wing nut 62 cooperable on the flange 49 for securing the arm 56 in position.

30 Inside the tube 15 I slidably mount an inner-tube 63 which has its upper end threaded at 64 for connection with the neck 65 of the head 66. A suitable roller bearing assembly 67 is interposed between the upper end of the outer tube 35 15 and the inner-tube 63. Inner-tube 63 may be shifted inside the outer tube 15 for raising and lowering the head 66 but is restrained from relative rotary movement. In Figure 1 I illustrate a bracket 68 as having its lower end positioned in 10 a socket 69 in the base 10 and its upper end bolted at 70 to the outer tube 15. Bracket 68 is slotted at 71 for the reception of a lever 72 pivotally connected at 73 with the bracket 68. The inner end of the lever 72 projects through 45 a slot 74 in the outer tube 15 and its inner end extends through an opening 75 in the inner-tube 63. It will thus be seen that the inner-tube 63 may be elevated through downward movement of the outer end of the lever 72. Opening 75 is 50 of sufficient proportion to loosely receive the inner end of the lever, while slot 74 is of sufficient length to accommodate the necessary shifting of the lever for elevating the inner-tube and consequently the head 66. Figure 1 illustrates the inner tube 63 or the head 66 in its normal 55 position.

Neck 65 is hollow and communicates with the hollow tubular part 76 of the head 66, see Figure 4. The mill plate to be resharpened is indicated 60 at 77 and is detachably connected with a flange 78 through the medium of screws 79 extending through openings in the mill plate and threaded into flange 78. Flange 78 is keyed at 80 to a lead screw or shaft 81 having one end rotatably 65 journaled at 82 in a closure plug 83 having threaded relation at 84 with the tubular part 76 of the head 66.

Plug 83 may be provided with sockets 85 for the reception of a suitable wrench to facilitate 70 placement of the plug. The plug may be made secure by a set screw 86.

To the opposite end of the tubular part 76 I connect a plate 87 through the medium of bolts 88 threaded into the end of the tubular part. 75 Plate 87 includes a boss 89 having a threaded

opening 90 for threaded relation with the threaded reach 91 on the lead screw or shaft 81. A ratchet wheel 92 is keyed at 93 to the outer end of the shaft or lead screw 81. Ratchet wheel 92 includes teeth 93 about its peripheral face and the number of the teeth 93 corresponds to the number of the channels 94 in the mill plate 77. Ratchet wheel 92 is rotated one tooth at a time for turning the mill plate 77 a corresponding distance for bringing the next grinding position into 10 grinding relation with the grinding wheel 39. Rotation of the ratchet wheel 92 one tooth at a time imparts slight axial movement to the lead screw or shaft 81 for advancing the mill plate 15 77 a corresponding distance in the direction of the grinding wheel 39 to compensate wear of the latter.

Adjacent the inner face of the plug 83 I mount a friction disk 95 which is held in pressure relation with the closure plate through the medium 20 of a washer 96 keyed at 97 to the shaft 81 and urged against the friction disk through the medium of a compression spring 98 having one end arranged in pressure relation with the washer 96 and its opposite end lying against a thrust 25 bearing 99 abutting the plate 87. It will thus be seen that the shaft 81 while rotatably mounted is restrained from accidental rotary movement because of the breaking action of the friction disk 95 which bears against the plug 83 keyed to the 30 flange 78. Keyed connection 97 permits relative longitudinal movement of the shaft 81 with respect to the washer 96.

Upon the reduced extension 100 projecting beyond the ratchet wheel 92 and comprising a part 35 of the shaft 81 I mount a pall actuating lever 101. Lever 101 rotates freely on the shaft part 100 and is bent to provide a parallel reach 102 which supports one end of a pin 103 having its other end supported by the lever 101. A pawl 104 is pivotally mounted on the pin 103 and is yieldingly urged into pressure relation with the ratchet wheel 92 by a spring 105 having one end fixedly connected at 106 with the cross reach 107 interconnecting the reach 102 with the lever 101. Pawl 104 is shifted through the medium of the lever 101 sufficiently far to be brought into abutting relation with the next tooth on the wheel 92 for rotating the wheel upon pivotal movement of the lever 101 in the opposite direction. 45

Figure 4 illustrates the opposite end of the lever 101 as being bent to extend across the face of the ratchet wheel 92 and inwardly of its opposite side, as at 108. The lever is further bent at 109 to provide an arm 110 which parallels the tubular part 76. To the outer tube 15 I connect a bracket 111 through the medium of bolts 112. The vertical run of the bracket comprises a shaft threaded at 113 for the reception of lock nuts 114 constituting a stop or rest for the arm 110. Figure 1 illustrates the normal relation between the arm 110 and the stop 114. I anchor a companion stop 115 to the plate 87 slightly underneath the upper face of the stop 114. Stop 115 may comprise a bolt threaded into the plate 87. 50 A tension spring 116 has one end secured at 117 to the arm 110 and its opposite end secured at 118 to the boss 89. Raising of the head 66 lifts the arm 110 off the rest 114 while at the same time the spring 116 will pull arm 110 downwardly 55 for moving the far end of the lever 101 upwardly sufficiently far to bring the pall 104 into engagement with the next tooth on the ratchet wheel 92. The stop 115 is spaced beneath the supporting face of the stop 114 sufficiently far to permit 60 70 75

the necessary pivotal movement of the lever 101, but acts to prevent further pivotal movement after the pawl 104 has been shifted into latching relation with the next tooth. Upon lowering of the head 66 the arm 110 will be brought into engagement with the stop 114 after which further lowering of the head causes the lever 101 to pivot in the opposite direction thereby rotating the ratchet wheel 92 in the direction of the arrow 119 of Figure 6 a distance equal to the space between two teeth. Lock nuts constituting the stop 114 may be adjusted on the bracket 111 to secure precise adjustment for the arm 110.

Within the innertube 63 I mount a tension spring 121 one end of which terminates in a wire 122 fastened to the shaft or lead screw 81, as at 123 in Figure 4. The opposite end of the spring 121 terminates in a wire 124 which is connected with an eye 125 secured to a support 126 made secure inside the base 10 by a set screw 127. Spring 121 operates to exert a downward pull on the hinge 66. Elevation of the head extends the spring 121 so that its increased tension is effective on the head for lowering purposes although the head tends to drop by gravity alone in the absence of lifting forces on the lever 72.

Outer tube 15 is provided with diametrically opposed longitudinal slots 128 within which slide blocks or keys 129 are positioned. Keys 129 include projections 130 which ride in slots 131 in the innertube 63. Extensions 130 restrain the innertube 63 from relative rotary movement but permit free longitudinal movement with respect to the outer guide tube 15. The outer guide tube 15 may be provided with a stop 132 arranged to engage one of the slots 129 for limiting the upward position of the head 66. Stop 132 is adjustable through the medium of a screw 133 which is also true of the block 129 because of the screw 134.

Within the post 13 I mount a cushioning spring 135. One end of the spring rests on the support 126 while its opposite end embraces the lower end of the innertube 63 and abuts a cross pin 136 passing to the innertube. Spring 135 functions as a cushioning means for the head as it is lowered, but the weight of the head together with the pulling force of the spring 121 is more than sufficient to overcome lifting tendencies of the spring 135.

From the foregoing description of the various parts of the device the operation thereof will be readily understood. The grinding stone 39 may be adjusted for angularity through rotation of the base plate 26 about the axis of the vertical reach of the post 18. Pointer 31 indicates the degree of angularity while adjustment of the nut 29 secures the base plate 26 in the position of selected angularity. The forward position of the grinding stone 39 is determined through the medium of the screw 42 which moves the gear box 36 bodily relatively to the guide 32. The forward or grinding position of the stone 39 is indicated by the pointer 54 while tightening of the screw 53 secures the gear box in fixed relation to the guide 32. Pointer 54 may comprise a separable part secured to the gear box 36 by a screw 138.

Figure 7 illustrates the channels 94 as being arranged tangentially of the mill plate 77 but the channels on the side 138 will successively assume vertical alignment for presentation to the grinding stone 39. Figure 1 illustrates the lowered position of the head 66 at which time the highest part of the mill plate 77 is located beneath the

horizontal center line of the stone 39. After the grinding stone 39 has been adjusted to the proper cutting position with respect to the mill plate 77, the lever 72 is pivoted downwardly which elevates the head 66 and moves the mill plate 77 across the face of the grinding stone 39. The channels 94 terminate considerably short of the central axis of the mill plate so that the movement of the mill plate across the grinding face of the stone may be considerably less than the diameter of the mill plate.

Immediately upon lifting of the head 66 the arm 110 moves downwardly because of the tension of the spring 116 until the arm comes to rest on the stop 115. Stop 115 limits further pivotal action of the pall lever 101 as the head 66 continues its upward movement but the pivotal action of the lever 101 is sufficient to shift the pall 104 into engagement with the next tooth on the ratchet wheel 92. As the head 66 is lowered the highest point of the mill plate 77 drops beneath the horizontal center line of the grinding stone 39 before the arm 110 is brought into abutting relation with the stop 114. As the arm 110 engages the stop 114 further downward movement of the head 66 rotates the ratchet wheel 92 a slight distance for advancing the mill plate 77 towards the grinding stone 39 thereby compensating wear of the latter.

Teeth 93 on the peripheral face of the ratchet wheel 92 are spaced so that the pall 104 will rotate the mill plate 77 one channel at a time for presentation to the grinding face of the stone 39. The entire face of the mill plate 77 may be resharpened through manipulation of the lever 72. The friction disk 95 which is cooperable on the washer 96 keyed to the shaft 81 restrains the shaft from accidental rotary movement so as to render the pall 104 certain and accurate in its turning action on the ratchet wheel 92. An oil cup 139 may be connected with the head 66 and communicates with the interior thereof. Drive pulley 38 may be connected with any suitable source of power through the medium of a conventional feed belt.

What is claimed is:

1. A device for resharpening channeled mill plates comprising a grinding means, a guide, a standard slidably related to the guide for movement in a reciprocatory path, a head carried by said standard, a mill plate mount including a shaft rotatably journaled in said head, a screw connection between the shaft and the head, a ratchet wheel fixedly connected with said shaft, said ratchet wheel having teeth corresponding in number to the channels in the mill plate, and pall means including an operable connection with said guide for rotating the shaft to advance the mill plate to successive grinding position as the head is reciprocated, said screw connection operating to advance the mill plate mount towards the grinding stone, to compensate wear of the latter.

2. A device of the type described comprising a grinding stone, a work mount, a support, a shaft keyed to the work mount and threadedly related to said support for rotation therein, a relatively fixed guide, a companion guide fixed to said support and slidably related to said fixed guide, means for actuating said companion guide to shift the support and said work mount for presenting the work to the grinding stone, and an operating connection between said relatively fixed guide and said shaft for turning the latter to shift the work mount for advancing the work to

- successive grinding positions with respect to said grinding stone and for advancing the work mount toward the grinding stone, to compensate for wear of the latter.
5. 3. A device of the type described comprising a grinding stone, a work mount, a support, a shaft keyed to the work mount and threadedly related to said support for rotation therein, a relatively fixed, vertical guide, a companion guide fixed to 10 said support and slidably vertically of said fixed guide, said work mount normally being positioned beneath said grinding stone, means for elevating said companion guide to lift the support and said work mount for presenting the work to the 15 grinding stone, and an operating connection between said relatively fixed, vertical guide and said shaft for turning the latter to shift the work mount for advancing the work to successive grinding positions with respect to said grinding stone 20 and for advancing the work mount toward the grinding stone, to compensate for wear of the latter.
4. A device of the type described comprising a grinding stone, a work mount, a support, a shaft 25 keyed to the work mount and threadedly related to said support for rotation therein, a relatively fixed, vertical guide, a companion guide fixed to said support and slidably related to said relatively fixed, vertical guide, means for elevating 30 said companion guide to shift the support and said work mount for presenting the work to the grinding stone, and an operating connection between said relatively fixed, vertical guide and

said shaft for turning the latter to shift the work mount for advancing the work to successive grinding positions with respect to said grinding stone as said support and the work mount approach their normal positions beneath the grinding stone, said shaft being shifted axially when rotated for advancing the work mount toward the grinding stone, to compensate for wear of the latter.

5. A device of the type described comprising a 10 grinding stone, a work mount, a support, a shaft keyed to the work mount and threadedly related to said support for rotation therein, a relatively fixed, vertical guide, a companion guide fixed to 15 said support and slidably related to said fixed guide, means for elevating said companion guide to shift the work support and said work mount for presenting the work to the grinding stone, an operating connection between said relatively fixed guide and said shaft for turning the latter 20 to shift the work mount for advancing the work to successive grinding positions with respect to the grinding stone as the support and the work mount approach their normal positions beneath the grinding stone, rotation of said shaft 25 advancing the work mount toward the grinding stone, to compensate for wear of the latter, and resilient means cooperable with said relatively fixed, vertical guide and said shaft for urging the support and the work mount to their normal positions beneath said grinding stone.

JOSE C. H. LEON.
